UNITED STATES PATENT OFFICE

LEO GANZ, OF CHICAGO, ILLINOIS

WATER HEATER

Application filed February 10, 1926. Serial No. 87,315.

This invention relates to water heaters, and more particularly to water heaters of the uniflow type.

It contemplates more especially the provision of means constituting individual heating stations designed to uniformly distribute the generated heat in the combustion chamber, and to effect a uniform rise in temperature along a definite line of water flow, which 10 in this instance constitutes a series of baffle plates arranged so as to expose a maximum radiating or absorbing surface to the hot combustion gases issuing from the burner element.

15 Other systems have heretofore been employed in water heaters of this character, but these have not proven entirely satisfactory, because of their complex and expensive construction, their inefficiency, and their inability 20 to efficiently supply hot water instantaneously. Previous attempts have been made to utilize the heat inherent in the waste flue gases, but because of insufficient heat absorbing surfaces, and also in view of the fact that 25 the water was not evenly heated, it was impossible in devices having the above noted characteristics, to utilize the heat which ordinarily was discharged to the atmosphere with the flue gases.

30 Further, devices of this character require a great deal of attention in their operation with the result that such expedients like pressure gauges, thermostatic controls, and the like are necessary to avoid danger and inconvenience. These are very costly and rather unreliable.

One object of the present invention is to improve the construction and operation of devices of the character mentioned.

40 A further object is to apply the heat to the water carrying vessels so intimately that less fire will be required and therefore considerably less fuel used.

Another object is the provision of a more 45 efficient, and less complicated device of the above mentioned type. This is accomplished in the present embodiment by providing unusually large heat absorbing surfaces through which water circulates in the path of burner elements arranged to concentrate the heat of

combustion at intervals along the line of water flow.

Another object is to provide means whereby the heat is more evenly distributed throughout the combustion chamber. 55

A further object is to provide means whereby the water is caused to twirl so as to uniformly distribute the heated water particles with the result that instantaneous heating is effected, and the stresses on the heater due 60 to uneven heating, eradicated or at least minimized to negligible proportions.

A further object is to arrange the heat absorbing surfaces in such a manner as to completely utilize practically all of the heat 65 inherent in the products of combustion before their escape from the combustion chamber to the atmosphere.

A still further object is the provision of an automatic control for automatic heaters 70 which does not necessitate the use of a thermostat or other complicated and expensive expedients.

Other objects and advantages will appear 75 from the following description of an illustrated embodiment of the present invention.

In the drawings:

Figure 1 is a sectional view of a water heater constructed in accordance with the present invention. 80

Figure 2 is a sectional view taken substantially along line 2—2 of Figure 1.

Figure 3 is a diagrammatic plan view showing the manner in which the stand pipes unite the individual water chambers. 85

Figure 4 is a fragmentary sectional view taken substantially along line 4—4 of Figure 1.

Figure 5 is an enlarged fragmentary sectional view taken substantially along the line 90 5—5 of Figure 4.

Figure 6 is a perspective view of a water valve piston shown in Figure 4.

Figure 7 is a fragmentary sectional view of an individual baffle section constituting a 95 water chamber.

The water heater selected for illustration comprises a cylindrical shell 10 supported upon suitable standards 11 which are secured to the lower portion of the shell in any suit- 100

able manner as by the bolts 12. A curved cover 13 of standard construction rests upon the shell 10 and is secured thereto by swaging the periphery 14 thereof around the upper 5 rim 15 of the shell 10. The cover has an opening 16 defined by the upstanding flange 17 which is centrally disposed with reference to the shell, and is adapted to receive a pipe 18 which leads to a chimney flue or any other 10 appropriate exit which will direct the escape of the flue gases to the atmosphere. A tubular burner element 19 which in this instance is curved to define a helix, is provided with a series of Bunsen burners 20, 21, 22 and 23, 15 arranged at intervals along the burner pipe 19. This burner element is disposed near the bottom of the shell and is adapted to receive suitable gaseous or liquid fuel from a valved housing 24 which communicates with the 20 burner pipe 19 and is connected therewith by means of a union 25. As shown the housing 24 is provided with a port 26 which is adapted to receive a pipe 27 leading from any suitable fuel supply source. The pipe 27 as shown, 25 communicates with the housing 24 by means of an internally threaded upstanding flange 28 provided for that purpose. A plug 29 of standard construction is detachably secured to the end of the burner pipe 19 to 30 facilitate access thereto in the event that cleaning of the burner element is necessary.

The interior of the shell 10 comprising the combustion space or chamber is provided with a series of baffle plates 30, 31, 32, 35 33 and 34 constituting water chambers consisting of substantially circular, parabolic, concavo-convexo lens-shaped sections (Figure 7) arranged to pocket the heated gases which issue directly thereto from their respective burner elements by virtue of flues to 40 be hereinafter described. As shown, the baffle plates are arranged in such a manner as to completely cover the combustion space, thereby obstructing the combustion gases which 45 impinge against their surfaces during their travel upwards in an endeavor to reach the chimney pipe 18. This is desirable in that the water which circulates through the very narrow water space 36, is permitted to contact with a very large heat radiating surface 50 as is obvious from the showing in Figure 7.

The baffle sections in the present showing, are connected in series by virtue of water 55 tubes 37 which communicate with each of the sections in such a manner as to give the water a decided twirl during its passage therethrough. This is accomplished by arranging the sections in juxtaposition, and by arranging the tubes to substantially define a helix 60 (Figure 3) so that they extend from the upper central portion 38 to the periphery of the next succeeding section as at 39 thus directing the water tangentially inside the periphery of the baffle sections and causing the 65 water—by virtue of its spiral course in the

tubes 37 and the circular wall of the said periphery—to assume a twirling motion within the baffle sections.

Water is supplied from any convenient pressure source through a pipe 40 which communicates with a housing 41 secured in coaxial relation with the housing 24. These housings 24 and 41 which constitute a passage way for the fuel and water, respectively, are separated from each other by means of a 70 plug 42 (Figure 4) which prevents intermingling of the fuel and water. An elbow 43 is arranged at the end of the housing 41 and is secured thereto, in this instance, by virtue of the threaded internal bushing 44 75 which also serves as a guide for the water valve to be hereinafter described. The elbow 43 terminates in a pipe 45 which leads to and communicates with the periphery of the lowermost baffle section 30 so as to establish a water flow through each individual baffle plate, and ultimately to the outlet 46 which leads from the uppermost baffle section 34 to any desirable fixture adapted to dispense water, such as a faucet. As shown, 80 the pipe 46 extends through the cover 13 of the shell 10.

It is desirable to concentrate heat under each baffle section in order to uniformly distribute the heat in the combustion chamber as well as to steadily increase the temperature of the water as it passes through each section which may be regarded as an individual heating unit. With this end in view, the Bunsen burners and the baffle plates have 85 a peculiar cooperative arrangement in a spiral course. To begin with, the helical burner pipe 19 is laid in close proximity to the wall of the shell 10, and its burners are built up with tubular columns 47, 48, 49, and 50 to carry the mixed fuel to elevated points for combustion. Each of the burner columns 47, 48, etc., is directed to apply its flame under a corresponding baffle plate 30, 31, etc. As the burner columns are uniformly spaced 90 in spiral succession, so are the respective baffle plates disposed in their lateral arrangement. This arrangement enables one portion of each plate to be close to the wall of the shell at a point above the corresponding burner columns 47, 48, etc., these columns lining the wall because of the proximity of the burner pipe 19 thereto. Thus, the flame 95 issuing from each column is received into the concavity of the baffle plate from one end and deflected and pocketed in the balance of the concavity to fully heat the plate. Consequently, a small flame will suffice to heat each baffle plate, effecting a 100 considerable saving in fuel over existing types of instantaneous water heaters. Further, the projection of the heat from the sides toward the center of the shell, and the concentration thereof within the elevated region of the plate concavities will leave the lower 105

110 concavities of the plate to receive the flame 115 from the next succeeding burner column. This 120 arrangement insures a uniform heating of the water throughout the entire shell. The water 125 passes through the tubes 37 in a helical course, and is caused to circulate by the action of the 130 water valve 42 which is controlled by the pressure of the water in the housing 41.

part of the shell relatively cool—and especially so near the wall of the shell—so that the fuel will not light at the burner nozzles 20, 21, etc., from "backfiring" action of the flames, at the top of the burner columns. The novel arrangement thus assures the uninterrupted and efficient operation of the flames. The ascending course of the burner pipe is designed to render the burner columns more or less uniform in length, whereby to save material in the manufacture thereof. The arrangement of the baffle plates incidentally gives the heat ascending therefrom a tortuous path of travel, so that it will remain in longer contact with the surfaces of the baffle plates, to be absorbed thereby before reaching the outlet flue in the top of the shell. By this arrangement practically all of the heat is utilized from the flames and products of combustion before reaching the chimney pipe 18 which communicates with the atmosphere.

The burner columns, above mentioned, terminate at the lower ends in spaced standards 51 which are secured to the burner element 19 above each nozzle by welding or the like, thereby permitting access of air to the burner.

The uppermost baffle section 34, in this instance, is of such size as to cover practically the entire combustion chamber in an effort to extract any heat that may remain in the products of combustion after their passage through the lower sections. An opening 52 centrally disposed with respect to the combustion chamber and situated immediately below the chimney pipe 18, is provided in the baffle section 34 to permit the escape of the cooled flue gases to the atmosphere. In order to retard the escape of the flue gases so as to enable complete extraction of heat therefrom, a plate 53 of any desirable shape is employed to restrict the opening 52, and may be provided with adjusting means so as to enable regulation of the rate of discharge through the opening 52. The plate 53 may be termed a damper, for it governs the amount of draft through the heater. It will be noted however, that the baffle section 34 does not touch the periphery of the shell 10, and therefore a means of escape for the gases is always maintained.

It is to be emphasized that in the construction shown, the baffle sections are so constructed as to provide a very thin water chamber 36 of comparatively large surface area with a view to provide a heat absorbing surface of unusually large magnitude. It is desirable that the thickness of the chamber 36 should not be in excess of three sixteenths ($\frac{3}{16}$) of an inch, thereby directing a thin sheet of water therethrough which is exposed to a heat radiating surface of unusually large magnitude. Such a construction and arrangement is conducive to effi-

cient and instantaneous heating, especially in view of the above described method employed to direct the heat against the radiating surfaces. The arrangement shown is also a novel feature and helpful in attaining the desired effect, in that it consumes very little space, and imparts to the water a twirling movement when circulating through the system, thereby uniformly distributing the heated water particles and thoroughly commingling the same with the cooler water particles. This feature is highly desirable in that it makes possible the high efficiency obtainable in the construction above described. Further, it eliminates the unusually high temperature difference of the water in different sections of the system which is very marked in heaters of the usual construction. Needless to say that an uneven distribution of heat subjects the heater to harmful stresses occasioned by marked variances in temperature. These undesirable effects are entirely eliminated in the system embodying my invention.

It is ordinarily undesirable to provide automatic controls for the admission of fuel and water to the heater especially because such devices require a great deal of attention to insure efficient and safe operation. To avoid the inconvenience necessitated by such devices, an automatic control is provided having a construction wherein the regulation of fuel and water is controlled without the use of a thermostat or other expensive and complicated expedients. In this instance, the automatic control is entirely mechanical in that its operation is dependent upon the water flow occasioned by its consumption, so that the expansion of the heated water in the system produces a back pressure which affects the flow through the controller, thereby effecting the control of the fuel. This control reacts to static and dynamic forces established by the expansion and flow of water respectively, through a movable member which reciprocates in the housings adapted to receive fuel and water. The water control member is connected by suitable connecting means, with a fuel valve mounted for simultaneous movement with the water valve.

Referring now more to Figure 4 wherein a structure illustrative of the automatic control embodying the present invention is shown, it comprises a fuel and water housing 24 and 41 respectively united in coaxial relation and by virtue of an internal union 42. The union is arranged to divert the flow of fuel and water in different directions to prevent intermingling thereof. As shown, the union 42 is provided with an axial bore 54 adapted to receive a piston rod 55 which is mounted for reciprocation in the housings 24 and 41. An inner chamber 56 provided in the housing 41 communicates with a chamber 57

extending through the elbow 43. An externally threaded bushing 44 within the chambers 56 and 57 joins elbow 43 with the housing 41 thereby forming a continuous passage to the baffle sections by means of the pipe 45 interposed between the elbow 43 and the stand pipe 37 in the usual manner. A disc 58 having axially extending guiding lugs 59 on its periphery is secured to the piston rod in any suitable manner, in this instance, by means of a nut 60 which is in threaded engagement with the extremity of the piston rod 55. A fuel valve having a valve body 61 is housed within and between the housing 24 and the burner element 19, and serves as a connection therefor, in that the union 25 secured to the burner element 19, is adapted to engage the external threads 62 of the valve body. The valve body as shown, is provided with the annular passages 63 and 64 which communicate with each other through a restricted port 65 which receives the needle piston valve 66 having an enlarged conical head 67 which is adapted to bear against the port 65, thereby obstructing passage of fuel from the chamber 63 to the chamber 64. The piston valve 66 is secured to the other extremity of the piston rod 55 in any appropriate manner, and is reciprocal with the piston rod 55. A plate 68 having perforations 69 for admitting fuel therethrough, is provided on the inlet face of the valve body 61 to act as a guide for the piston valve 66 which reciprocates in the axial bore 70 of the face plate 68. It is to be noted that the plate 68 is substantially rectangular in form and being narrower than the diameter of the chamber 63, admits the passage of fuel around it as clearly shown in Figure 5. Packing 71 is placed around the piston rod 55 in an axial opening 73 provided in the plug 42 so as to prevent leakage between the water and fuel housing 24. A threaded plug 74 having a central opening to receive the rod 55, is detachably secured into the bore 73 so as to retain the packing in place.

With the arrangement of parts as described above, the water flow through the water inlet pipe 40 establishes pressure against the piston valve 58 thereby pushing the valve with its rod to the left, thereby permitting the water to flow into passage 56 to the baffle sections by means of any convenient piping as described above. Simultaneous with the movement of the water valve to the left, the fuel valve 66 is simultaneously shifted, thereby establishing communication between the chambers 63 and 64 which supplies fuel to the burner element 19. It will be noted that the rate of discharge of hot water through a convenient dispensing means connected to the outlet pipe 46 controls the amount of water flowing into the system. The water flow opens the water valve which admits a quantity of unheated water propor-

tional to the quantity tapped, thereby maintaining the system filled at all times. Obviously an admission of water admits fuel also, since the water and fuel valves have the same movement. To insure the valve to assume its normally closed position during a period of no water flow, a coil spring 75 is placed around the rod 55 between the fuel valve 66 so as to abut against the plug 42. When the static pressure in the hot water system is equal to the pressure of the water supply source, the spring 75 will cause the valve 66 to bear against its seat 65, thereby preventing an admission of fuel to the burner. It is to be noted that with the valve construction shown valve adjustment and regulation is possible by merely changing the distance between the internal bushing 44 and the fuel valve body 61.

It is important or at least highly desirable to avoid the escape of unburned fuel especially when gaseous fuel is employed, which would occur when the burners 20 to 21 etc., are extinguished; therefore a pilot burner 76 communicating with the chamber 77 of the housing 24 is designed to supply at all times just enough fuel to provide a light capable of effecting combustion of the fuel issuing from the individual burners. In the present showing the pilot 76 consists of a rod receiving a small quantity of fuel from the chamber 77 which is directed to the uppermost extremity of the burner column 47 thereby igniting any fuel which will issue therefrom. It is obvious that individual pilot lights may be provided for each burner. Hand operated valves may be provided in the supply lines to enable the complete shut off of both the water and fuel to the heater whenever desirable.

The lower extremity of the shell 10, the interior of which constitutes the combustion chamber, may be closed by providing a diaphragm of any suitable form, having openings to allow the admission of air for draft purposes.

Various changes may be made in the embodiment of the invention herein specifically described without departing from or sacrificing any of the advantages of the invention as defined in the appended claims.

I claim:

1. In a water heater, having a series of vertically spaced plates of hollow construction, and water conductors inter-connecting the plates; the combination of a fuel conductor entirely below the plate assembly, and a series of direct burner columns upon said fuel conductor upwardly extended from the fuel conductor to the vicinity of the respective plates for the discharge of flame in the direction of the bottoms of the plates and thereagainst.

2. In a water heater, a series of vertically spaced and staggeredly arranged plates of

hollow construction, water conductors interconnecting the plates, a fuel main below the plate assembly and in the form of a rising spiral, and a series of burner columns directed from points along the fuel main to the vicinity of the plates in the order of the respective heights of the latter, for the discharge of flame against the same.

3. In a water heater, a substantially cylindrical shell, a series of vertically-spaced plates of hollow construction, water conductors interconnecting the plates, a fuel conductor below the latter and having a spiral course in proximity to the wall of the shell, and a series of burner columns directed from points along the fuel conductor to the vicinity of corresponding plates for the discharge of flame thereagainst, said burner columns being close to the walls of the shell, and said plates being laterally arranged in spiral order whereby to expose unrestricted portions in proximity to the walls of the shell directly to the flames of the corresponding burner columns.

25 4. In a water heater, having a substantially cylindrical shell, and a series of water vessels in the upper part of the latter, the combination of a spiral fuel main in the lower part of the shell and having its course in proximity 90 to the wall thereof, and burner columns rising from the main to positions in the vicinity of said water vessels and discharging thereagainst.

5. In a water heater, a substantially cylindrical shell, a series of vertically spaced chambered water plates of substantially circular contour and concavo-convex formation, means connecting the chambers of successive plates and a burner opposite the concavity of each plate and discharging upwardly thereagainst, said burner being located near the edge of the plate and having its flame fill the plate concavity from the direction of such edge in a cup-shaped sheet.

45 6. In a water heater, a substantially cylindrical shell, a series of vertically spaced chambered water plates of substantially circular contour and concavo-convex formation, said plates being diametrically smaller than the shell being laterally distributed to locate the outer section of each plate close to the wall of the shell, and a burner opposite the concavity of each plate and discharging upwardly against the bottom thereof at the site of its said outer section, said burner having its flame fill the plate concavity toward the center of the shell in a cup-shaped sheet.

7. In a water heater, a series of vertically-spaced plates of substantially circular contour, said plates also being hollow to accommodate a sheet-like body of water, a series of conduits for successively connecting said plates and entering the same tangentially at the periphery, and leaving said plates at substantially the center, the supply forming a

water body in each plate which is composed of inherent currents describing a twirling spiral commencing at the supply and ending at the discharge.

8. In a water heater, the combination of a series of vertically spaced plates of hollow construction, water conductors interconnecting the plates, a fuel conductor below the plate assembly, said plates being arranged so that each has a portion in direct and unobstructed alinement with said fuel conductor, said fuel conductor having burner outlets, and vertical conduits carried by said fuel conductor and surrounding each of the burner outlets, each of said conduits extending 70 75 toward the exposed portion of one of said plates and discharging against the bottom thereof.

In testimony whereof I affix my signature at 10 South La Salle Street, Chicago, Illinois. 80 85
